UNITED STATES PATENT OFFICE.

JOHN HOBBS, OF BOSTON, MASSACHUSETTS.

AGITATOR FOR KETTLES OR TANKS.

SPECIFICATION forming part of Letters Patent No. 447,566, dated March 3, 1891.

Application filed June 20, 1890. Serial No. 356,100. (No model.)

To all whom it may concern:

Be it known that I, JOHN HOBBS, a citizen of the United States, residing at Boston, in the county of Suffolk and Commonwealth of 5 Massachusetts, have invented certain new and useful Improvements in Agitators for Kettles and other Vessels, of which the following is a full specification.

My invention consists of an improved adjustable agitator and mixer adapted especially for use in kettles for melting fats in the manufacture of oleomargarine oil, or for rendering lard, tallow, &c. The agitator is provided with mechanism for raising and lowering the 15 same and with appliances for keeping up a circulation of water or steam within it while revolving in the kettle or other vessel containing the fats or other substances to be stirred. While especially adapted for treatment of fats, as above, it is, moreover, useful in apparatus for extracting the strength from 20 drugs or for any purpose wherein it is desirable to carry heat or cold to the center or interior of a substance or mixture while agitating.

Referring to the accompanying drawings, Figure 1 is an upright view, partly in section, showing the agitator applied to a kettle for treating fats, the agitator being shown in position for operation within the kettle. Figs. 30 2 and 3 are plan views of details, and Fig. 4 is a view showing the agitator raised out of the kettle.

I will proceed for convenience to describe 35 my apparatus as adapted for use with a kettle for melting and mixing fats, calling attention to the fact that its construction and operation are similar in the main for the various other purposes to which it is adapted.

40 A is an outer and A' an inner kettle, the two being preferably bolted together, as by bolts b, so as to leave a space a between the sides and bottoms thereof.

E is a vertical shaft seated at the bottom 45 in a bearing-block F, within the inner kettle, and at the top in the bearing-block F'. This shaft derives motion through the bevel-gears B B', the gear B' being fixed thereon and meshing with the gear B, the shaft B' of 50 which is arranged to revolve whenever the agitator is to be operated. The agitator

proper consists in this case of a system of piping K, so arranged as to form stirrers or paddles, and firmly secured to a sleeve E', which slides on the shaft E, being fastened 55 to said sleeve in any desired manner, as by connections k. The sleeve E' is fastened to the shaft E so as to turn therewith by means of the set-screw e². The sleeve is, moreover, movable up and down on the shaft, 60 and is preferably provided with a circular doubly-flanged top E², either integral with said sleeve or secured thereto. Between the flanges of the top E² fits loosely the circular strap e, Fig. 2, which is held stationary as the sleeve revolves by means of the arm e' engaging at its outer end with the rest e³ on the side of the inner kettle A'.

H H are chains connected with opposite sides of the strap e and serving as means for 70 lifting the agitator out of the kettle when desired. To this end the said chains pass over pulleys I I on each side, as shown in the drawings, and are attached to weights W of sufficient size to counterbalance the weight of the 75 agitator and its connections.

The shaft E at its upper end revolves within any suitably-constructed stuffing-box, as f, constructed in such a manner that an outer steam or water pipe L may communicate in a 80 perfectly tight manner with a passage l, bored out in the shaft E, when the said shaft revolves.

L' is a tube or pipe connected to the shaft E and communicating with the passage l. 85 This pipe L' extends downward, and when the agitator is in position for operation, as shown in Fig. 1, is connected by means of the coupling l' with a pipe l², passing through a hole in the flanged top E² of the sleeve E', the pipe 90 l² being in turn connected with the system of piping K, forming the agitator near the top thereof. This pipe l² is the inlet-pipe to the agitator. The outlet consists of a pipe L² arising from the bottom of the system K and terminating at the top in a bend L³, forming a 95 spout to discharge condensed steam or water.

G, Fig. 3, is a stationary annular pan held suspended above the flanged top E² of the sleeve E' by hooks or links h, connected with 100 the chains H or in any other desired manner, as by separate chains or ropes from above.

G' is an outlet-pipe from the pan G, preferably passing along the arm e' and secured, as at g, thereto. This pipe has a downward slope and discharges its contents either, as shown 5 in the drawings, into the space a between the inner and outer kettles, or, if desired, into a separate waste-pipe. The construction and arrangement are such that as the agitator, and with it the pipes l' and L', revolves the said 10 pipes l' and L' pass around within the annular pan G, while the pipe L' discharges its contents into said pan, whence it flows out through the pipe G'. In this manner steam or water may circulate constantly through the 15 agitator, heating or chilling, as desired, the interior of the substance within the kettle while said substance is being stirred.

When it is desired to raise the agitator out 20 of the kettle for the purpose of allowing the fats to settle after being stirred and mixed or for any other purpose, the set-screw e² is first loosened and the coupling l' unscrewed. The agitator is then turned slightly till an appropriate hole in the flanged top E' comes directly 25 under the pipe L', when it is raised to any required height, together with the pan G and its connections, by lifting on the chains H H.

The kettle in connection with which the agitator is used in the present instance is 30 preferably so constructed that water or steam can be introduced around the inner kettle in the space a, as well as in the interior thereof, through the agitator. With this in view the pipe C' enters the space a near the bottom of 35 the outer kettle, and into this pipe run both the water-pipe C, controlled by the valve c, and the steam-pipe S, controlled by the valve s. In this way either water or steam may be introduced at will. N is the waste or over- 40 flow pipe, running out of the outer kettle near the top thereof.

When the fats or other materials in the kettle have settled after the stirring and mixing operations, the lighter substances may be 45 drawn off from the top down to any required depth in the manner shown in Fig. 4 by means of the pipe D, jointed near the bottom of the inner kettle to communicate with the outlet-pipe D'. The heavier substances at the bottom 50 of the kettle may be drawn off separately through the outlet-pipe P, controlled by the valve P'.

While I preferably construct my agitator in the manner described, with the system of piping so arranged that the bends in the pipe 55 themselves form the stirrers, I may apply the same principle to agitators already in use, wherein there are separate paddle-blades, by carrying the piping around said blades and securing it thereto.

I claim—

1. The combination, with a kettle or other vessel, of a vertical shaft, a stuffing-box, a sleeve embracing said shaft and revoluble with and movable up and down upon said 65 shaft, a system of piping secured to said sleeve, and suitable inlet and outlet passages constructed and arranged substantially as described.

2. The combination, with a kettle or other 70 vessel, of a vertical shaft, a stuffing-box, a sleeve embracing said shaft and revoluble therewith, a system of piping secured to said sleeve, suitable inlet and outlet pipes, and a stationary annular pan, substantially as described. 75

3. The combination, with a kettle or other vessel, of a vertical shaft, an agitator revoluble with and movable up and down upon said shaft, a stationary lifting-strap suitably connected with said revoluble agitator, and suitably-guided chains connected to said strap and provided with counterbalancing-weights, substantially as described. 8c

4. The combination, with a kettle or other 85 vessel, of a vertical shaft, an agitator revoluble with and movable up and down upon said shaft, provided with a circulatory system of piping and suitable inlet and outlet passages, a stationary strap suitably connected with 90 said revoluble agitator, and suitably-guided chains connected to said strap and provided with counterbalancing-weights, all constructed and arranged substantially as and for the purposes described. 95

In witness whereof I have hereunto set my hand.

JOHN HOBBS.
